[57] CLAIM

The ornamental design for a bird cage, as shown and described.

DESCRIPTION

FIG. 1 is a side elevational view of a bird cage showing my new design;
FIG. 2 is an elevational view taken from the side opposite that shown in FIG. 1;
FIG. 3 is a top plan view thereof; and
FIG. 4 is a bottom plan view thereof.

FIG. 1.

FIG. 2.

FIG. 3.

FIG. 4.
